UNITED STATES PATENT OFFICE

147,131

DESIGN FOR A LIGHTER

James Keenan, Los Angeles, Calif.

Application January 19, 1946, Serial No. 125,765

Term of patent 3½ years

(Cl. D48—27)

To all whom it may concern:

Be it known that I, James Keenan, a citizen of the United States and resident of the city and county of Los Angeles, State of California, have invented a new, original, and ornamental Design for a Lighter, of which the following is a specification, reference being had to the accompanying drawings, forming a part thereof, in which:

Fig. 1 is a top plan view of the lighter showing my new design;

Fig. 2 is a bottom plan view; and

Fig. 3 is a side elevation thereof.

I claim:

The ornamental design for a lighter, substantially as shown.

JAMES KEENAN.
